HEEL BREASTING MACHINE

Fred P. Taylor, Auburn, Maine, assignor to United Shoe Machinery Corporation, Flemington, N. J., a corporation of New Jersey

Application August 12, 1944, Serial No. 549,181

10 Claims. (Cl. 12—47)

This invention relates to trimming machines and is illustrated as embodied in a heel breeding machine.

Various types of machines, each having a reciprocating knife movable past a shearing edge to breast unattached heels, have been proposed. It has been found, however, that unless such machines are precision machines, which are expensive to manufacture, there is a tendency for the upper breast edge of the heel, formed by the knife in emerging from the heel while making the breeding cut, to have leather fibers, sometimes referred to as "whiskers," extending therefrom. Such projecting fibers cause said edge of the heel to have a ragged appearance and are usually removed in a separate operation before the attachment of the heel to the shoe.

It is an object of the present invention to provide a simple non-precision machine having none of the above-mentioned drawbacks by the use of which unattached built-up leather or leatherboard heels may be quickly and effectively breasted.

With the above object in view and in accordance with a feature of the present invention, there is provided, in a trimming machine for use in breeding heels, for example, a rigid support for an unbred heel, said support having an edge, a block of resilient material constructed and arranged to be engaged by a portion of the heel extending beyond said edge and to cause the heel upon the support initially to be spaced from said edge, and a reciprocating knife movable past said edge, the block being yieldable under pressure of the heel operated upon by the knife to permit a portion of the heel to be forced against and tensioned crosswise of said edge preparatory to the severance of material from said portion of the heel.

In the illustrative machine the rigid support has a work receiving face which is inclined at approximately 30° to the horizontal and forms with a flat vertical face at the lower end of the support an edge toward and past which a cutting edge of the reciprocating knife is moved in effecting its breeding cut. In engagement with the vertical face of the support is a rubber block the upper horizontal work supporting face of which extends outwardly from said edge of the support. Arranged adjacent to and extending above the horizontal face of the rubber block is a breast gage for positioning the unbred heel lengthwise upon the rigid support and the rubber block which together may be said to form a re-entrant cutting bed, with the rear end of the

attaching face of the heel in engagement with the inclined surface of the rigid support and the forward end of the attaching face of the heel in engagement with the horizontal face of the rubber block, an intermediate portion of the attaching face of the heel being spaced from said edge of the rigid support. The heel, if desirable, may be positioned widthwise upon the cutting bed by a gage shaped and arranged to be engaged by the side of the heel.

As the knife descends into engagement with the tread face of the unbred heel mounted upon the cutting bed, it forces the forward end of the heel into the rubber block, permitting said intermediate portion of the attaching face of the heel to be forced against said edge of the support, with the result that portions of the attaching face of the heel in the vicinity of said edge are tensioned crosswise of the edge. When the knife moves through said tensioned portions of the heel adjacent to said edge and past said edge, the attaching face breast edge of the heel is cut clean. After the heel breeding chip has been trimmed from the heel and the knife starts to rise, the rubber block springs back to its original shape and position, causing the chip trimmed from the heel to be ejected over the breast gage and out of the machine.

The above simple, non-precision heel breeding machine will quickly and effectively breast unattached built-up leather heels, a clean cut being formed where the knife cuts through the heel, even though the cutting edge of the knife misses the work support edge of the cutting bed by a substantial margin.

The various features of the invention will be understood and appreciated from the following description read in connection with the accompanying drawings, in which

40 Fig. 1 is a side view of the illustrative machine;
Fig. 2 is a rear view of the upper portion of the machine;

Fig. 3 is an enlarged angular view, partly broken away, of a cutting bed of the machine;

45 Fig. 4 is a section on line IV—IV of Fig. 3;

Fig. 5 is a side view showing a portion of the cutting bed with a heel positioned on it ready to start the breeding operation;

50 Figs. 6 and 7 are enlarged longitudinal sections showing the action of the work engaging portions of the machine on the heel during two different stages of the heel breeding operation;

Fig. 8 is a perspective view of the unbred heel which is to be operated upon by the machine; and

Fig. 9 shows the heel of Fig. 8 after it has been breasted by the above machine.

The illustrative machine is described with reference to trimming an unbreasted heel 20 (Figs. 3, 4, 5, 6 and 8) comprising a plurality of leather or leatherboard lifts to provide a breasted heel 22 (Figs. 7 and 9).

The unbreasted heel is positioned, as will appear later and as best shown in Figs. 3 and 5, upon a cutting bed 24 (Figs. 1, 3 and 5) comprising a rigid support or table 26 which is secured by screws 28 (Figs. 1 and 3) to a bracket 30 fastened to a frame 32 (Figs. 1 and 2) of the machine by screws 34.

Slidably movable in vertical guideways 36 (Fig. 1) of the machine frame 32 is a slide 38 operatively connected to a treadle 40 through a link 42. The treadle 40 is mounted upon a furcum pin 44 carried by the machine frame 32 and when the machine is idle is held in its raised inoperative position, shown in Fig. 1, by a spring 46. Upward movement of the treadle 40 is limited by the engagement of the upper end of the slide 38 with a cover plate 48 secured by a screw 50 to the upper part of the machine frame. The machine has only two legs and is secured by suitable clamps (not shown) in an upright position against a wall.

Formed integral with and extending forward from the slide 38 is a carrier lug 52 (Figs. 1 and 2) provided with a vertical groove 54 in which fits a shank portion of a knife 56 having at its lower end a cutting edge 58 (Figs. 2 and 3) the end portions of which are straight and the central portion of which is incurved. The knife 56 is secured to the carrier lug 52 by a clamp plate 60 forced against the knife by a pair of screws 62. To insure against displacement of the knife 56 as it is forced against the heel, there are provided thrust screws 64 threaded into the carrier lug 52 and having their lower ends in engagement with the upper end of the knife.

The table 26 is angle shaped (Figs. 1 and 3) as viewed from the side of the machine and comprises a face or work plate 66 (Figs. 3, 5, 6 and 7) which is secured by screws 68 (Fig. 3) to the main portion of the table, flat upper faces 70, 72 of the main portion of the table and the work plate, respectively, being in alignment and inclined at approximately 30° to the horizontal. The unbreasted heel is positioned lengthwise on the table 26 by a breast gage or abutment 74 which is secured to the bracket 52 by screws 75 and against which the forward end of the unbreasted heel rests.

As best shown in Figs. 5 and 8, the attaching face or cup 76 of the unbreasted heel 20 is concave, the maximum concavity being approximately $\frac{1}{8}$ of an inch. Accordingly, in order effectively to support the forward end of the unbreasted heel, the work plate 66 has an upstanding protuberance 78 (Figs. 3 and 5) the upper face of which is approximately complementary to opposed portions of the forward end of the attaching face of the heel. A forward edge 80 (Fig. 3) of the protuberance 78 forms with straight edges 82 of the plate 66 a continuous edge past which the cutting edge 58 of the knife 56 passes when said knife is moved downward upon depression of the treadle 40. The cutting edge 58 of the knife 56 lies in a single plane and, as above explained, has a central concave portion and lateral straight portions, the cutting edge of the knife being approximately complementary to the combined edges 80, 82 of the work plate 66. It will be apparent

from the foregoing that, in breasting the heel, the various portions of the cutting edge 58 of the knife 56 move approximately the same distance below opposed portions of the edges 80, 82 of the plate 66. The breast gage 74 has a raised central portion 84 (Figs. 3 and 5) similar in shape to and arranged opposite the protuberance 78, the arrangement being such that the breast gage 74 throughout its width extends approximately a constant distance above the opposing portions of the continuous edges 80, 82 of the work plate 66.

In order to insure against a rear vertical face of the protuberance 78 interfering with the presentation of unbreasted heels to the machine, there is provided a filler piece 86 which is secured by screws 88 (Fig. 3) to the main portion of the table 26 and has a longitudinally and laterally beveled upper surface forming substantially a continuation of the upper surface of the protuberance 78.

The heel is usually centralized upon the table 26 with sufficient accuracy by sliding it down over the filler piece 86 and onto the protuberance 78 to the position shown in Fig. 3. If desirable, however, an edge gage 90 (Figs. 3 and 4) may be provided, such a gage comprising a flange 92 which is engaged by a side of the heel being positioned in the machine. Secured to an offset downward extension of the flange 92 is a rod 94 a portion of which fits in a transverse bore 96 (Fig. 4) of the table 26. The edge gage 90 may be moved into different adjusted positions lengthwise of the bore 96 to move the inner face 35 of the flange 92 into alignment with any one of several size calibrations 98 (Fig. 3) on the table, by turning a nut 100 which is threaded onto the rod 94 and is constantly forced against a side of the table 26 by a spring 102 (Fig. 4).

A true shearing action between the edges 80, 82 of the work plate 66 and the cutting edge 58 of the knife 56 cannot be relied upon since the illustrative machine is not of the "precision" type. In the illustrative machine, which is simple and inexpensive, the knife 56 is preferably so guided that it clears the edges 80, 82 of the work plate 66, said clearance, as shown in Fig. 7, being slightly exaggerated for purposes of illustration, thereby insuring that were the knife to spring slightly or to have its path of movement otherwise changed during the heel breeding operation, it will not strike the edges of the work plate. It has been found that unless a resilient work supporting block 106, which cooperates with the rigid support 26 and will later be referred to in detail, is provided, the knife 56 in cutting through the attaching face 76 of the heel forms an upper breast edge which has fibers or "whiskers," such as above referred to, extending from it. Such a ragged edge, of course, is objectionable and is usually buffed or otherwise trimmed before the heel is attached to the shoe.

The resilient block 106, which is preferably made of live rubber, is interposed between the breast gage 74 and a vertical face 104 of the work plate 66, forwardly and rearwardly extending elements of the upper face of the block being arranged approximately horizontally. The upper face of the rubber block 106 is provided with a centrally located upwardly extending protuberance 108 (Figs. 3 and 5), the upper face of which corresponds generally in shape to the upper face of the protuberance 78 of the work plate 66 and is approximately complementary to the forward 75 end portion of the attaching face of the smallest

beginning about 15 mm. at the right end in unbreasted heel to be operated upon by the machine. The upper face of the rubber block 106 extends forwardly to the edges 80, 82 of the work plate 66 and may be referred to as a horizontal step portion of the cutting bed of the machine, the upper surface of the rigid portion of the support 26 constituting an inclined work supporting portion of the cutting bed. The rubber block 106 is preferably compressed slightly between the breast gage 14 and the vertical face 104 of the work plate 66, which face may be described as forming with the upper surface of the work plate the edges 80, 82 and as being in approximate alignment with the path of movement of the cutting edge 58 of the knife 56. The unbreasted heel 20 is initially positioned upon the cutting bed 24 (Figs. 3 and 5) with the rear end of its attaching face in engagement with the flat face 70 of the rigid portion of the table 26 and the front end of its attaching face resting upon the upper face of the rubber block 106, the heel being positioned lengthwise on the cutting bed by the breast gage 14 and being positioned widthwise on said bed by the protuberance 78 and/or the flange 92 of the edge gage 90. It will be noted (Fig. 5) that the unbreasted heel 20 in its initial position upon the cutting bed 24 has its attaching face 76 spaced from the edges 80, 82 of the work plate 66.

When pressure is first applied against the heel by the downwardly moving knife 56, the forward end of the heel is forced into the rubber block 106, as shown in Fig. 6, until the attaching face of the heel has been forced against the edges 80, 82 of the work plate 66. As the knife 56 continues to descend, it moves slightly below the edges 80, 82, as shown in Fig. 7, the knife missing said edges by a slight margin, as above explained, and pushing slightly into the upper portion of the block 106. It will be apparent that before the knife 56 moves past the edges 80, 82 of the work plate 66, fibers of the portions of the unbreasted heel lying just above said edges, which, as above stated, are in effect one continuous edge, are tensioned crosswise of said edge because of the upward force applied against the heel by the compressed rubber block 106, with the result that the knife in cutting through the heel trims such tensioned fibers clean, thereby forming a clean-cut attaching face edge of the breast of the heel.

The rubber block 106 may be described as being yieldable under pressure of the knife to permit a portion of the heel to be forced against and tensioned crosswise of the edges 80, 82 of the work plate 66 preparatory to the severance of said portion of the heel. It will be noted that the rubber block 106 projects above a downward continuation of the face 72 of the work plate 66 and is compressible in order to permit the heel to be forced against the edges 80, 82 of the work plate. Accordingly, the rubber block 106 may be defined as constituting a salient portion of the cutting bed 24, or as being raised with relation to the general level of the face 72. Moreover, in view of the fact that the heel supporting faces of the rigid support 26 and the rubber block 106 are arranged approximately in angular relation to each other, such faces may be said to form a re-entrant cutting bed, or to form substantially an obtuse dihedral angle.

When the heel has been breasted and the knife 56 starts upward, the rubber block 106 assumes its initial position and shape, causing a chip 110 (Fig. 7) trimmed from the heel to be deflected upwardly and to the left, with the result that said

chip tumbles rearwardly over the breast gage 14 and out of the machine.

Having described my invention, what I claim as new and desire to secure by Letters Patent of the United States is:

1. In a trimming machine, a rigid support for a work piece, said support having an edge, a block of resilient material constructed and arranged to be engaged by a portion of the work piece projecting beyond said edge and to cause said work piece upon the support initially to be spaced from said edge, and a reciprocable knife movable past said edge, said block being yieldable under pressure of the work piece operated upon by the knife to permit a portion of the work piece to be forced against and tensioned crosswise of said edge preparatory to the severance of material from said portion of the work piece.

2. In a trimming machine, a work supporting bed, said bed comprising a rigid support having an edge and a salient resilient work supporting block arranged adjacent to said edge, a reciprocable knife mounted for movement past said edge to trim material from the work, and means for operating the knife to cause portions of the work extending beyond the edge of the rigid support to be forced into the block thereby permitting portions of the work to be forced against and tensioned crosswise of said edge preparatory to the severance of said portions of the work.

3. In a trimming machine, a knife having a cutting edge, means for reciprocating said knife, a rigid support having angularly disposed surfaces forming an edge, one of said surfaces being constructed and arranged to be engaged by a work piece and the other of said surfaces being arranged in approximate alignment with the path of movement of the cutting edge of the knife and overlapping to a slight extent said path of movement, and a block of resilient material which is in engagement with the portion of the surface of the support along which the knife moves, said block having a work piece engaging surface forming substantially an obtuse dihedral angle with adjacent portions of the work piece engaging surface of the rigid support.

4. In a trimming machine, rigid and resilient supports provided with faces respectively which are approximately continuous and form a re-entrant cutting bed, said face of the rigid support having an edge, a knife having a cutting edge movable past said edge of the rigid support, said faces of the rigid and the resilient supports being constructed and arranged to be engaged initially by opposite ends respectively of a work piece with an intermediate portion of the work piece spaced from said edge, and means for actuating the knife to cause the resilient support to be compressed under the action of the work piece operated upon by the knife thereby permitting the work piece to be moved into engagement with said edge of the work support and tensioning portions of the work piece located adjacent to the edge crosswise of said edge preparatory to moving the knife past said edge completely to sever said portions of the work piece.

5. In a breasting machine, a rigid support constructed and arranged to be engaged by the attaching face of an unbreasted heel, said support having an edge, an abutment for positioning the heel lengthwise on the support, a knife, means for reciprocating the knife toward and past said edge of the said support to breast the heel, and a block of resilient material interposed between the abutment and the support, the

block being constructed and arranged to be engaged by the forward end of the attaching face of the unbreasted heel and to cause the heel initially to be spaced from said edge of the support, said block being yieldable under pressure of the heel operated upon by the knife to permit an attaching face portion of the heel to be forced against and tensioned crosswise of said edge of the rigid support preparatory to the severance of said attaching face portion from the heel.

6. In a breasting machine, a rigid support for an unbreasted heel, an abutment constructed and arranged to be engaged by the forward end of the heel to position said heel lengthwise on the support, a block of resilient material which is constructed and arranged to be engaged by the forward end of the attaching face of said heel, and a knife for breasting the heel, said block being constructed and arranged to be compressed during the heel breasting operation and after said operation to expand causing a chip trimmed from the heel to be ejected from the machine.

7. In a breasting machine, a rigid support for an unbreasted heel, said support having an edge, an abutment which is spaced from the support and is constructed and arranged to be engaged by the forward end of the heel to position the heel lengthwise on the support, a block of resilient material interposed between the abutment and the support and constructed to be engaged by the forward end of the attaching face of the heel, and a knife movable toward and past said edge of the rigid support to breast the heel, said block being compressed by the heel during the heel breasting operation and after said operation expanding to cause a chip trimmed from the heel to be ejected from the machine.

8. In a breasting machine, a knife having a cutting edge, means for reciprocating said knife, a rigid support having angularly disposed surfaces forming an edge, one of said surfaces being constructed and arranged to be engaged by the attaching face of an unbreasted heel and the other of said surfaces being in approximate alignment with the path of movement of the cutting edge of the knife, a breast gage constructed and arranged to be engaged by the forward end of said heel to position the heel lengthwise on the support, and a rubber block which is clamped between the breast gage and said other surface

of the support and is constructed and arranged to be engaged by the forward end of the attaching face of the heel, said block being raised with relation to the general level of the heel engaging surface of the rigid support and being compressed to permit a portion of the heel to be forced against and tensioned crosswise of the edge of said rigid support preparatory to the severance of said portion of the heel.

10. 9. In a breasting machine, a cutting bed comprising an inclined rigid portion the front lower end of which terminates in an edge and a resilient step portion extending forward from said edge, said cutting bed being constructed and arranged initially to support a work piece with a portion thereof spaced from said edge, and a reciprocatory knife having a cutting edge movable toward and past said edge against the resilient step portion of the cutting bed, said resilient step portion of the cutting bed being compressed under the action of the work piece operated upon by the knife to permit the work piece to be moved into engagement with said edge of the rigid support of the cutting bed and to cause fibers of the work piece adjacent to said edge to be tensioned crosswise of said edge preparatory to moving the knife past said edge completely to sever material from the work piece.

10. In a breasting machine, a cutting bed for supporting an unbreasted heel, said cutting bed comprising an inclined rigid portion the lower end of which terminates in an edge and a resilient step portion extending approximately horizontally from said edge, said inclined and step portions of the cutting bed being constructed and arranged to be engaged initially by the rear and front portions respectively of the attaching face of the heel, intermediate portions of the heel being spaced from said edge of the rigid portion of the cutting bed, a reciprocatory knife movable toward and past said edge, and means for operating the knife to cause the heel under the action of the knife to compress the resilient step portion of the support thereby permitting the heel to be moved against said edge and causing fibers of the heel positioned adjacent to and extending across said edge to be tensioned preparatory to moving the knife past said edge to sever material from the heel.

50 FRED P. TAYLOR.
